UNITED STATES PATENT OFFICE.

GROVER C. FARRIS, OF NORFOLK, VIRGINIA, ASSIGNOR TO CLIFTON E. ANDERSON, OF OCEAN VIEW, VIRGINIA.

CARBURETOR.

Application filed June 22, 1921. Serial No. 479,681.

To all whom it may concern:

Be it known that I, GROVER C. FARRIS, a citizen of the United States, residing at Norfolk, in the county of Norfolk and State of Virginia, have invented new and useful Improvements in Carburetors, of which the following is a specification.

This invention relates to carburetors and more particularly to that class of carburetors in which the richness of the combustible mixture is controlled by a sliding venturi shifttable with respect to the mouth of the main fuel nozzle.

One of the objects of this invention is to produce a carburetor which is characterized by a construction in which there is no auxiliary admission of air at high speeds of the motor with which said carburetor is used, and in which the entire air supply comes in by a main channel the excess richness of mixture incident to the absence of air being corrected not only by a shifttable venturi such as is usual in some carburetors, but by means of cutting off the idling jet more, or less or entirely, at high speeds of the motor.

Another object of the invention is to provide throttle operated means for cutting off the idling jet when the throttle is opened to a predetermined extent.

A further object of the invention is to so associate the venturi and idling jet closing means that both are operated by the opening of the throttle.

Still another object of the invention is to flexibly connect the throttle to the venturi so that sudden opening of the throttle will be accompanied by gradual rising of the venturi so as to prevent starvation of the engine due to sudden falling in the velocity of the air past the main fuel jet.

Another object of the invention is to provide a flexible connection between the throttle and venturi and means to hold the venturi in depressed position against the opening movement of the throttle for the purpose of priming.

With the above and other objects in view, my invention consists in the improved carburetors illustrated in the accompanying drawings, described in the following specification, and particularly claimed, and in such variations and modifications thereof as will be obvious to those skilled in the art to which my invention relates.

In the drawings accompanying and form-

ing a part of this specification, and wherein the preferred embodiment of my invention is illustrated:

Figure 1 is a vertical section of my improved carburetor with the throttle closed.

Figure 2 is a similar view of the upper portion of the carburetor showing the throttle open.

Figure 3 is a vertical section of the upper portion of the carburetor shown in Figure 1 viewed from the left.

Figure 4 is a horizontal section taken along the line 6—6 of Figure 1.

Figure 5 is a similar view taken on the line 7—7 of Figure 1.

In the drawings the main casting 1 of the carburetor is provided with an air inlet chamber 2 and an upright cylindrical mixing chamber 3 in communication therewith. The wall of said mixing chamber is bored out at 4 to form an idling well having a narrow passage-way 5 extending longitudinally of the wall of said mixing chamber and communicating therewith at a point 54 adjacent the edge of the throttle valve 6 when the latter is in closed position forming an idling nozzle 54 controlled by the needle valve 55. The casting 1 is also provided with a float chamber 8 which communicates by a horizontal bore 9 with the idling well and with the main fuel nozzle 10 which opens into the mixing chamber 3 through a narrow orifice 11. The casting 1 is bored out at 12 forming a socket which is threaded for the reception of a liquid fuel supply pipe not shown. Said bore 12 is in communication with a sediment chamber 13 into which opens the passage 14 controlled by the float valve 15.

To the float valve is secured a metallic float 16 determining the level of liquid fuel in said float chamber. The float is controlled by the usual weighted levers 17 which are pivoted at 18 to depending lugs 19 forming part of the cover 20 of the float chamber.

The bottom of the sediment chamber 13 is closed by a plug 21, by the removal of which the sediment may be drained. The plug 22 which carries the seat 23 of the float valve 16 and the passage leading thereto, is also removable by withdrawing it through the opening occupied by the nut 24 upon removing the latter. The main fuel nozzle 11 is screwed to the upper wall of the transverse

passage 9 and is insertable from the underside of said passage through an aperture closed by the plug 25. Another aperture in the lower wall of the passage 9 and closed by a plug 26 is in alignment with the idling well 4. Upon removal of the plugs 25 and 26 access is obtained both to the idling well and main fuel nozzle of the carburetor. These plugs are conveniently reached by 10 taking off the removable bottom portion 27 of the air inlet chamber which is detachably secured to the casting 1 by the thumbnuts 28 passing through apertured lugs 29 and 30 integral with said casting 1 and member 27 respectively.

The choke valve 31 is pivotally mounted in the end of the air inlet passage 2 and is operated by a bell crank 32 from the outside of the casting. The bushing 33 of the main 20 nozzle which carries the orifice 11 is detachably secured to said main-fuel nozzle and may be exchanged for a bushing having an orifice of different size according to the requirements of the motor with which the 25 carburetor is intended to be used.

Slidably arranged within the mixing chamber 3 in operative relation to the main fuel nozzle 11 is a venturi 34 provided externally with grooves 35 and 36 in its upper 30 and lower ends carrying packing rings whose function it is to seal the space between the walls of the venturi and mixing chamber. The function of the sliding venturi is to change the cross sectional area of the passage around the main fuel nozzle and so to 35 vary the proportions of the combustible mixture.

The venturi 34 is directly connected to the throttle operating mechanism by a pair of 40 spiral springs 37 secured to pins 38 which project from the venturi intermediate its ends at diametrically opposite points, through slots 51 in the wall of the mixing chamber. These slots lie between the piston 45 rings throughout the range of movement of the latter and are thus sealed against communication with the interior of the mixing chamber. The other ends of said springs are made fast externally of the mixing chamber to ends of crank arms 50 fixed to the opposite ends of the shaft 39 on which the 50 throttle valve 6 is mounted. A lever 40 fixed to one end of the shaft 39 leads to manual operating means not shown. By virtue 55 of the resilient connection 37 between the venturi and the throttle valve operating mechanism a sudden opening of the throttle valve will result in a gradual elevation of the venturi due to the inertia of the venturi, 60 and the strength of the spring 37 being of such relative value to the weight of the venturi as to obtain this effect.

The resilient connection 37 also permits positive depression of the venturi even when 65 the throttle valve is open, for the purpose of

enriching the mixture for priming during cold weather. To this end the yoke 41 is provided which straddles the outside of the mixing chamber and bears upon the upper sides of the pins 38 of the venturi. The 70 yoke 41 is pivotally secured to pins 42 secured in longitudinal flange portions 43 which extend along the opposite sides of said mixing chamber. Said flanges are slotted adjacent said pins to permit the 75 swing of the yoke 41.

To the outer end of the yoke 41 is secured a cable 44 passing over a pulley 45 extending to a manual control not shown. By pulling on the cable 44 the ends of the yoke will 80 bear against the pins 38 of the venturi depressing the latter against the tension of the spring 37 regardless of the position of the throttle.

The pulley 45 is secured in a lug 46 made integral with the outer wall of the mixing chamber and a shock absorbing spring 47 is attached to said lug and to the yoke to maintain the ends of said yoke in easy resilient 85 contact at all times with the pin 38. 90

The longitudinal flanges 43 are joined by transverse flanges 44 forming a frame on each side of the mixing chamber which cooperates with a removable door 45 providing an enclosure in which the actuating 95 means for the venturi are maintained protected from dust.

It is usual in carburetors for the idling nozzle to open into the mixing chamber at a point near the edge of the throttle valve 100 when the latter is in closed position for the reason that when the throttle valve is closed the passage between said valve and the wall of the mixing chamber is restricted so that the suction is concentrated at the idling 105 nozzle. As the throttle valve is opened to increase the area of the air passage between said valve and the wall of the mixing chamber, the suction diminishes, and a smaller quantity of fuel is drawn through the idling 110 nozzle.

In a wide open position of the throttle valve there will of course be the least suction on the idling nozzle, but there is always some suction, and therefore an over 115 richness of mixture to this extent.

Instead of resorting to the expedient of admitting auxiliary air to the mixture conduit between the carburetor and engine, the present invention obviates the necessity for auxiliary air by the provision of a lip 52 attached to the venturi, which acts as a slide valve closing the idling nozzle 55 when the venturi is elevated. Being fixed in its relation to the venturi the idling nozzle closing 120 means partakes of all the flexibility of movement relative to the throttle valve of which the venturi itself is capable, being automatically moved to closing position when the throttle valve is opened and depressed 125 130

along with the venturi to enrich the mixture by operation of the manual means 44.

While I have above described what I have found to be a very practical embodiment of my invention, it is nevertheless to be understood that the carburetor may also be exemplified in numerous other alternative constructions and I accordingly reserve the right of adopting all such legitimate changes as may be fairly embodied within the spirit and scope of the invention as claimed.

Having described my invention what I claim as new and desire to secure by Letters Patent, is:—

1. In a carburetor, a mixing chamber, a throttle valve therefor, a main fuel nozzle opening into said chamber, an idling fuel nozzle in communication with said chamber, means for closing said idling nozzle, means resiliently connecting said throttle with said idling nozzle closing means, arranged to move the latter to closing position when the throttle is opened.
2. In a carburetor, a mixing chamber, an air passage leading thereto, a main fuel nozzle opening into said passage, an idling nozzle in communication with the mixing chamber, a throttle valve, means for varying the cross sectional area of said air passage adjacent the main fuel nozzle, a valve for said idling nozzle carried by said means and means for resiliently connecting said throttle valve and said area varying means.
3. In a carburetor, a mixing chamber, having an air passage leading thereto, a venturi slidable in said mixing chamber, a main fuel nozzle opening into said air passage, said mixing chamber being slotted ad-

acent said venturi, pins secured to said venturi and passing through the slotted portions of said mixing chamber, means connected to said pins for lifting said venturi, a yoke pivotally mounted in the wall of said mixing chamber, and bearing at its ends on said pins of said venturi, means for resiliently lifting said venturi, means connected to said yoke tending to move said venturi resiliently in a direction in opposition to the pull of said lifting means, said venturi being movable in said last named direction independently of said yoke.

4. In a carburetor, a mixing chamber, an air passage leading thereto, a main fuel nozzle opening into said air passage, an idling nozzle in communication with the mixing chamber, a venturi in said mixing chamber for varying the cross sectional area of said air passage adjacent the main fuel nozzle, a valve for said idling nozzle carried by said venturi, sealing rings mounted in spaced relation on said venturi engaging the wall of said mixing chamber, said wall being provided with a slotted opening intermediate the paths of travel of said sealing rings, operating means for said venturi projecting through said slotted openings, a throttle valve, and means for resiliently connecting said throttle valve and operating means.

In testimony whereof I have hereunto set my hand in presence of two subscribing witnesses.

GROVER C. FARRIS.
